UNITED STATES PATENT OFFICE.

EUGENE L. PERRY, OF WARREN, PENNSYLVANIA, ASSIGNOR TO THE ROGERS-SHEAR COMPANY, OF WARREN, PENNSYLVANIA, A CORPORATION OF DELAWARE.

ENVELOP-OPENER.

1,139,572.

Specification of Letters Patent. Patented May 18, 1915.

Application filed April 3, 1914. Serial No. 829,173.

To all whom it may concern:

Be it known that I, EUGENE L. PERRY, a citizen of the United States, residing at the village of Warren, in the county of Warren and State of Pennsylvania, have invented certain new and useful Improvements in Improved Envelop-Openers, of which the following is a clear, full, and exact description.

10 The object of this invention is to provide a simple, efficient and economical envelop opener of the shear type so that an envelop may be fed to the knife and the knife cut off just enough of the envelop to include 15 the double fold of the paper forming the edge without the possibility of cutting any enclosure within the same.

The scope of my invention will be pointed out in the claims.

20 In the accompanying drawings: Figure 1 is a central cross-sectional view on line 1—1, Fig. 2, of my improved device. Fig. 2 is a plan view of the same. Fig. 3 is a section on line 3—3, Fig. 1. Fig. 4 is a section on line 25 4—4, Fig. 3. Fig. 5 is a fragmentary section showing the position of an envelop against the cutter at the beginning of the cut before the envelop is pushed back. Fig. 6 is a diagrammatic view of the shear edges 30 upon insertion of an envelop. Fig. 7 is a diagrammatic plan of the shear edges at the completion of the cut.

As shown in the drawings, 1 is the envelop table, 2 is the waste box of a casting to 35 which, on 3, there is pivoted the cutter arm 4 carrying the shear-blade 5 and provided with an operating handle or knob 6. Springs 7, acting on plungers 8, tend to hold the reciprocating cutter in the position 40 in Fig. 1. A stop 9 striking against the end-wall 10 of the receptacle 2 limits the upward throw of the cutter. The movable shear blade, as particularly shown in Fig. 3, has its cutting edge 11 on an oblique line, 45 there being an extension 12 from its lowermost point which at all times is below the meeting edge of the stationary cutter 13. Immediately below the oblique cutting edge 11 of the shear-blade 5 is a beveled portion 50 14 so that upon inserting an envelop, par-

ticularly one that may be bulky and readily pushed into position so that the shear edge might cut the contents, the beveled surface 14 will push the envelop away from the movable cutter until only the extreme edge 55 of the envelop will be subject to the cutting edge 11 when it meets the stationary cutter 13. The stationary cutter 13 is freely mounted at the end of a rod 14^a and its upper edge is always held pressed against 60 the upper knife 11, in close relation with the beveled surface 14 by springs 15, as shown.

While one preferred form of the cutter has been illustrated and described, it is to be 65 understood that numerous changes may be made without departing from the invention.

I claim as my invention:

1. An envelop cutter, comprising a stationary rigid frame embodying a stationary 70 table portion constituting a support for the envelop, and a waste receptacle in rear of said table portion, a reciprocatory knife member fulcrumed on said frame at the rear of said waste receptacle and bearing an 75 upper blade removed from and approximately parallel to its fulcrum, a lower knife blade on the frame disposed in a substantially upright position at the back of the table portion and tilttable so as to carry its 80 upper edge transversely toward and from the reciprocatory blade, and springs at the table side of the lower knife blade for pressing the same against the reciprocatory blade.

2. An envelop cutter, comprising a frame 85 embodying a support for the envelop, a lower knife mounted on the frame, and a reciprocatory knife having an oblique cutting edge and a downwardly and rearwardly beveled gage surface beneath said edge operative to push the envelop outward beneath the cutting edge of the reciprocatory knife as the latter descends.

Signed at Warren, Pa., this 20th day of March one thousand nine hundred and four- 95 teen.

EUGENE L. PERRY.
